UNITED STATES PATENT OFFICE.

HERBERT F. SOWLE, OF EVERETT, MASSACHUSETTS.

DIVAN-BED.

1,295,935.

Specification of Letters Patent.

Patented Mar. 4, 1919.

Application filed April 25, 1917. Serial No. 164,379.

To all whom it may concern:

Be it known that I, HERBERT F. SOWLE, a citizen of the United States, residing at Everett, in the county of Middlesex and State of Massachusetts, have invented new and useful Improvements in Divan-Beds, of which the following is a specification.

The object of the present invention is to combine a folding bed with articles of furniture of the sort known as divans and davenport sofas, etc. My main and primary object is to provide such a folding bed structure as will cause the greater dimension of the bed when extended to be perpendicular, 15 that is transverse, to the longer dimension of the sofa when folded or collapsed. The fulfilment of this purpose enables a full length bed to be comprised, when folded, within the limits of a sofa, or divan, or the like, 20 which is shorter than the full length of a normal full grown person. The accomplishment of this purpose involves the making of a folding bed bottom in three sections so that the extended bed, which is long enough to 25 accommodate the normal adult, may be folded into a compass from front to rear not greater than the standard width of a sofa, the limits of which are fixed by the necessity of making it a comfortable seat. 30 In this description the terms "ends" and "sides" as applied to the folded up or compacted sofa or divan indicate directions transverse to the dimensions indicated by the terms "length" and "width" with respect to 35 the extended bed; these terms being used in connection with the sofa or divan and the bed, respectively, with their common significance when applied to sofas and beds which are separate from one another. Other 40 objects are concerned with the mechanical features of the folding divan bed whereby ease and efficiency of operation are secured, together with strength and compactness of structure.

Having thus set forth the general objects of the invention I will proceed now to a detailed description of one embodiment of the same shown in the drawings which accompany this application. In the drawings,

50 Figure 1 is a front elevation of the divan bed or sofa bed referred to, the same being in the closed or folded up condition.

Fig. 2 is a cross section of the same on line 2—2 of Fig. 1.

55 Fig. 3 is a plan view of the extended sofa bed, with parts thereof broken away.

Fig. 4 is a longitudinal section of the bed in the condition shown in Fig. 3.

Fig. 5 is a longitudinal section showing the parts of the bed in a position intermediate the closed up and fully open positions, this being one of the positions assumed by the parts when in course of being opened or closed.

The same reference characters indicate 65 the same parts in all the figures.

The outer frame of the sofa bed, which also may be called the stationary frame, is composed of two end pieces 11, 12 and transverse pieces or beams 13 and 14, both of 70 which are at the back of the stationary section, the beam 14 being at the top of the end pieces. There is also a transverse rod 15 between the end pieces at the forward side and bottom thereof, placed so low that the 75 movable section can readily pass over it. As concerns the main frame or stationary section the longest dimension is between the end pieces 11 and 12, and this dimension is called the length of the sofa. 80

A movable section is comprised by end frames composed preferably of fabricated structural steel having upper and lower horizontal beams 16 and 17, upright struts or posts 18 and 19 and diagonals 20, 21. 85 There is one such frame at each side of the bed, that is close within the end pieces of the stationary frame, and they are braced by cross beams 22 and 23. They are provided with foot portions 24 and 25 having 90 casters which roll upon the floor.

The forward posts 18 rise above the horizontal beams 16 and each carries a pivot stud 26 to which is connected an arm 27 on a swinging frame 28. Arms or frames at 95 opposite sides of the bed are connected or braced by a beam 29. At the upper rear corners of the removable section is pivoted a second swinging frame consisting of arms or beams 30 at each end of the sofa, and a 100 cross beam or brace 31 between these two arms, each of said arms being connected by a pivot pin 32 with one of the frames. Connected to each of the beams 30 is a forwardly extending arm 321, which is connected by a 105 pivot 33 with a link 34 which carries a pivot pin 35 passing through a short slot 36 in the adjacent beam 28 of the forward swinging section. The link 34 is duplicated at each side of the bed frame. On the rear end of the rear swinging section are studs 37 which preferably carry antifriction rolls 110

entering guideways or grooves 38 extending vertically, or substantially so, on the inner sides of the end pieces of the stationary section.

Attached to the beam 31 by means of a hinge 39 is a frame 40 which provides the back for the sofa when the bed is closed up and is swung back out of the way when the bed is extended. This frame may be upholstered in any desired manner. Connected to the end members of the frame 40 are webs 41 to each of which is pivoted at 42 one end of a link 43, the other of which is pivoted at 44 to a block or cleat 45 attached to the inner side of the end piece 11. Similar connection is made between the end piece 12 and the corresponding link at the opposite end of the sofa. In the upper side of each cleat 45 is a notch 46 adapted to receive extensions 47 from the ends of the cross beam 29 of the forward swinging section when the bed is closed up.

The bars 28, 16, and 30 at the opposite sides of the movable section are adapted to be placed in line with one another, and when thus extended they form the side bars of a bed frame, there being one set of these bars at each side of the bed frame. They are preferably made of angle irons according to the common practice in bed construction, whereby inwardly directed flanges are provided for connecting the springs of an articulated spring frame 48, which may be considered as typifying any of the common forms of bed spring. It may be noted, however, that the spring is made in two sections, that carried by the forward swinging part 28 being distinct from the other, which extends continuously from the forward end 40 of the middle section to the rear end of the rear swinging section 30. The bottom formed by this spring is adapted to support a mattress 49 which is made either in three separate parts or in three sections hinged together adjacent the pivots 26 and 32, respectively.

One point to which I call particular attention is that the pivot 26 is offset above the plane of the spring by a distance approximately equal to the thickness of the standard mattress. The purpose of so offsetting this pivot is, of course, to enable the forward section of the mattress to fold over upon the middle section, as indicated in Figs. 2 and 5 so that when these two parts of the bed are thus folded up plenty of room will be left between the sections of the spring to contain two thicknesses of mattress. The mechanical problem involved in thus offsetting the pivot is solved by extending the posts 18 above the plane of the bed bottom, and forming such posts of angle irons placed with their forward flanges at the front and projecting outwardly as indicated at 18^a in Fig. 3, and in providing pivot studs 26 of

excessively large diameter. The necessity of having a freely yielding bed bottom at the junction between the middle and forward sections, as well as elsewhere, makes impossible the insertion of a rigid brace between the bars 28 of the forward section at the end of such bars next to the middle section, to oppose the tension of the spring, which tends to pull these bars together. This pull must be opposed by the post 18 and the pivot studs 26. The flanges 18^a on the posts and the large size and greater strength of the studs, effectively hold these beams apart.

The opposite side of the forward section from that on which the mattress rests is upholstered as indicated at 50 to make a finished seat when the bed is folded. In order to follow out the operation of this simple mechanism when extending and folding up the bed, let us assume that the bed is folded as shown in Figs. 1 and 2. The parts are all then in the position clearly shown in Fig. 2. To extend the bed the user grasps some part of the movable section and pulls on it toward the front. I may provide handles or loops on any part of this structure which may be convenient for the purpose. Force so applied causes the central section to be trundled forward bodily, carrying the pivot 32 of the rear section 30. The upper end of this section being held by the studs 37 in the guideway 38 is restrained and can move only downward, which has the effect of swinging the rear section about the pivot 32. In this action the arms 321 acting upon the links 34 tend to swing the front section up and forwardly about the pivots 26. If the user takes hold of the beam 20 of this section and pulls on the same forwardly and upwardly at one time, he will cause the rear section to be swung backward through the agency of the links 34 and the middle section to be propelled forward. At the same time the descent of the part 31 on the rear swinging section causes the back frame to be turned about its pivot connection 42 with the links 43, which being movable allows this pivot axis to be shifted while the turning effect takes place. The design of the parts is such that by the time the bed is entirely extended, the back frame has been entirely reversed and is substantially in a vertical plane at the head of the bed. The rear end of the rear swinging section is then supported by the beam 13, in which are preferably mounted one or more spring lifters each comprised of a plunger 51 and a spring 52 beneath it in a socket in this beam. The function of the spring lifters is to raise the studs 37 out of the plane of the bed so as to facilitate closing the bed.

The forward swinging section is supported in a horizontal plane by the links 34 which are offset as shown at 53 so as to cross

the bars 16, such offset parts resting on the bars 16 and acting as stops to arrest the forward section when in the horizontal position.

- 5 To close up the bed the user first lifts up on the beam 29 of the front section, swinging the latter upward until the pivots 35 reach the end of the slots 36, whereupon the force applied through the links 34 on the arms 321 tend to lift the rear section. The force applied by the operator gradually changes its direction to a push toward the rear, being naturally diverted in that direction by the swinging of the front section. The swinging of the two end sections and the travel bodily at the central section all take place at the same time so that all arrive at once in the collapsed or folded position shown in Fig. 2, the back 40 being reversed and brought into position at the same time.

The reversible manner of mounting this back has an important advantage in the direction of compactness, simplicity, and efficiency. When the bed is folded up the back frame is directly in front of the rear section of the mattress, and rests against the same. As the back frame is preferably open, this part of the mattress is in effect a part of the upholstery of the back and adds to the comfort of the sofa. Then when the bed is extended this back frame is moved out of the way so as not to interfere with the movements of the rear bed section, some such movement being necessary because there is no space whatever between the back and the rear mattress section otherwise. Finally when the bed is fully extended the back frame is shifted slightly to the rear where it is exactly in the plane of the head of the bed and entirely out of the way of the occupant. I consider this means of providing a back when needed and disposing of it when not needed to be a valuable feature of the invention, particularly as it is accomplished automatically and without any care whatever on the part of the operator.

In the definition of the descriptive terms herein used I would say that the entire structure comprises two main sections, namely the relatively stationary section which is the outer frame of the sofa, and the movable section which constitutes the bed. The latter in turn is composed of three principal subsidiary sections, that is, the central section which rests upon the floor and is trundled over it, and the front and rear swinging sections which are pivoted to the central section. A noteworthy feature is that the two main sections can be easily disconnected by removing the hinges 39 and withdrawing the studs 37 from the guideways 38. Then the main frame of the sofa

bed proper and the bed section can be disassembled and separately packed for shipment. This is an important practical consideration because of the difficulty of securing the heavy and freely movable bed to the bulky sofa frame in such a manner that it will not break loose.

While the outer frame or stationary section co-acts with the movable section in forming a sofa when the bed section is collapsed, and in supporting the head end of the bed section, I do not limit my claims entirely to this combination, as I include also within the scope of the protection here sought, a folding bed having essentially the parts of the movable section or bed section of the combination, and without the sofa frame. The bed section alone may be converted from a bed to a sofa or couch, and vice versa, and may be made of such proportions that its length when extended may be greater than its width, or the reverse.

The terms "divan," "davenport," and "sofa" as used herein are not intended to have any limiting significance as to the type or character of furniture in which my folding bed construction may be embodied or incorporated.

What I claim and desire to secure by Letters Patent is:

1. A sofa bed comprising a sofa frame, a movable bed frame having a section adapted to form a seat for the sofa, and another section pivoted to the rear side of the bed frame and having its rear portion connected to the sofa frame and guided to move up and down relatively thereto, a back for the sofa comprising a frame, and means connecting said back frame to the sofa frame and to the rear part of said rear bed section, respectively, for causing the sofa back to be reversed when the bed is extended and collapsed, respectively.

2. A folding sofa bed comprising in combination a sofa frame, a bed frame inclosed within said sofa frame and being movable bodily out therefrom, a bed section hinged to said bed frame and slidably engaged with said sofa frame at its opposite sides, respectively, so as to shift between substantially upright and substantially horizontal positions, a sofa back hinged, when the bed is closed, at its upper edge to said bed section, and a pivot connection between an intermediate part of said back and the sofa frame arranged to cause reversal of the sofa back as the rear swinging section is moved up and down.

In testimony whereof I have affixed my signature.

HERBERT F. SOWLE.
